UNITED STATES PATENT OFFICE.

JOSHUA H. MARVIL, OF LAUREL, DELAWARE.

BASKET-COVER.

SPECIFICATION forming part of Letters Patent No. 350,376, dated October 5, 1886.

Application filed August 19, 1886. Serial No. 211,321. (No model.)

To all whom it may concern:

Be it known that I, JOSHUA H. MARVIL, a citizen of the United States, residing at Laurel, in the county of Sussex and State of Delaware, 5 have invented new and useful Improvements in Covers for Fruit-Baskets, of which the following is a specification.

The object of the present invention is to provide a strong, neat, and light cover for fruit-baskets, which is so constructed that when not in use a series of covers can be nested together or packed one within the other, so as to take up comparatively little space in storage or transportation, and thus obtain decided advantages over covers which require to be tied together or must be loosely shipped.

The invention consists in a cover which is formed of a series of slats, blocks, and fastening means, constructed and arranged in the 20 manner hereinafter fully set forth, and pointed out in the claims.

In the drawings, Figure 1 is a vertical sectional view of a fruit-basket provided with my improved cover. Fig. 2 is a perspective 25 view of the cover removed from the basket. Fig. 3 shows two covers nested together.

The reference-numerals 1 and 2 designate four sheets, strips, or pieces, which are of a uniform size or length, and are so shaped and 30 secured together as to form a frame of an octagonal shape. This latter form is given to the frame by cutting off each end of the strips or slats 1 and 2 to a square miter, or, in other words, cutting off said pieces obliquely and 35 matching and securing them together, so as to form the aforesaid octagonal frame. Blocks 3, running parallel with the mitered ends of the frame, are secured to the under side of parallel bottom strips or slats, 1. Nails or 40 other means are used for securing the blocks and the respective slats comprising the frame, and, as seen in Fig. 2, the blocks 3 extend diagonally across the slats and have their outer faces flush with the mitered portions of the 45 frame. The aforesaid slats 1 and 2 constitute a border-frame, as has been stated, and the middle of this frame is slatted across or covered with one or more slats, 4, which are secured to the slats 1, to which the blocks 3 are 50 directly secured.

The wires 6, generally resorted to for securing covers to fruit-baskets, are in the present instance inserted at two diametrically opposite corners of the cover, and are secured by

being clinched or bent down on the top surfaces of the slats 2. These wires 6 are passed through the divided rim of the basket, and are bent up around the outer hoop of such rim, so as to cause the blocks 3 to be firmly pressed down upon the rim of the basket and held in place upon the same until such time as the wires are straightened by hand to release the cover.

A cover constructed as shown is very easily and cheaply made, and is neat in appearance, 65 and by reason of the presence of the corner-blocks it is raised sufficiently far above the basket-rim to allow the basket to be heaped and its contents to be well exposed.

Another great advantage inherent in my 70 cover is that when it is not in use it can be nested with a series of others and made into a compact package, taking up comparatively little space, and resulting in a saving of return-freights when the baskets and covers are 75 returned to the shipper. It will be apparent that this nesting is made easy by the mitered corners of the frame and the blocks located thereat, and, referring to Fig. 3, it will be seen that the end slats, 1 2, of one cover lie in close 80 contact with the inner sides of a cover located beneath, and hence it follows that a series of covers will be held together by friction alone, and that no binding devices are required to prevent the displacement of a series of nested 85 covers during transportation or handling.

Having thus described my invention, what I claim is—

1. A cover for fruit-baskets, comprising an octagonal border-frame, one or more slats extending across said border-frame, and blocks running parallel with four alternate sides of said border-frame and secured to the under side thereof, substantially as described.

2. A cover for fruit-baskets, consisting of two pairs of parallel slats having mitered ends and secured together to form an octagonal frame, one or more cross-slats, the corner-blocks, and fastening-wires extending from two diametrically-opposite corner-blocks, substantially as described.

In testimony whereof I affix my signature in presence of two witnesses.

JOSHUA H. MARVIL.
